United States Patent Office.

SHELBY REED, OF SCOTTSVILLE, NEW YORK.

Letters Patent No. 88,211, dated March 23, 1869.

IMPROVEMENT IN SHEEP-RACK.

The Schedule referred to in these Letters Patent and making part of the same.

To all whom it may concern:

Be it known that I, SHELBY REED, of Scottsville, county of Monroe, and State of New York, have invented a new and improved Mode for Constructing Sheep-Racks; and I do hereby declare that the following is a full and exact description of the same, reference being had to the accompanying drawing, and to the letters of reference marked thereon, in which—

Figure 1 represents a perspective view of a three-tier portable sheep-rack.

Figure 2 represents a transverse section of my improved sheep-rack, showing three tiers, and bridges leading to the upper tiers.

The nature of my invention consists in the construction and arrangement of a portable sheep-rack, of two or more tiers, or stories, one above the other, in which more sheep can be fed and sheltered, in proportion to the lumber used in constructing the same, and to the space it occupies, than in any other sheep rack now in use.

To enable others skilled in the art to make or use my invention, I will proceed to describe the construction and arrangement of the same.

Fig. 1, in the accompanying drawing, represents a perspective view of a three-tier sheep-rack, with a feed-alley, marked *a*, through its centre.

Fig. 2, of same drawing, shows a transverse section of a three-tier rack as constructed by me.

The tiers, or racks are marked *b b b*, and are arranged on both sides of the centre, or feed-alley *a*.

The floors of the racks, marked *c c c*, are made tight, to prevent any impurities from falling through the floors on the sheep in the lower racks.

The floors *c c c* are also made slightly inclining toward the outside walls *g g*.

In the outside walls *g g*, and even with each of the floors *c c c* of the racks, or tiers *b b b*, are narrow openings, *d d d*, running lengthwise with each floor.

These openings are provided with hinged shutters *i i i*, as shown in drawing, fig. 1. The openings *d d d* are for the purpose of cleaning the floors *c c c*.

The mangers, marked *e e e*, are placed in the feed-alley *a*. They are always dry, and can be cleaned with ease. The feed can readily be distributed.

The rack, being portable, can be moved, with one open end, against a stack or barn-door. The opposite end may be closed by a door. The sheep and shepherd are thus protected from scathing winds and weather; also from crowding live stock.

The sheep ascend to the second and third stories, or tiers by guarded bridges *f f*, shown in drawing, figs. 1 and 2, which gratifies their natural propensity for climbing up to a dry and clean place to feed and ruminate.

More sheep can be fed and sheltered, in proportion to the lumber used in constructing my improved rack, and to the space that it occupies, than in any other rack now in use or known.

My rack can be made of cheap lumber, without a tenon or mortise.

A three-tier sheep-rack, constructed as shown in drawing, figs. 1 and 2, will accommodate six sheep to every foot in length.

Figure 3 is a perspective view of a sliding bar, which is made to cover the aperture through which the animals put their heads while feeding from the troughs *e*, it having slots formed in it, corresponding to those in the partitions which divide the apartments in which the sheep are kept from the central, or feeding-apartment.

It will be seen, by reference to the drawings, that when the shepherd desires to prevent the animals from feeding, he has only to move the slide, or bar into such a position that the bars thereof, which are left between the open spaces, will cover the open spaces between the slats in the partition, and thus cut off all access to the feeding-troughs.

Among the advantages due to my improvement may be mentioned the fact, that when the sheep are housed in this way, they are entirely safe from the attacks of dogs, wolves, or other animals which prey upon them.

What I claim as my invention, and desire to secure by Letters Patent, is—

1. Constructing a sheep-rack with three horizontal apartments, the two outer ones being for the reception of the animals, and the central one for the convenience of the person feeding the same, and two or more floors, or stories, one above another, all of which are arranged for the reception of animals, substantially as shown and described.

2. The arrangement of the sliding racks, or bars, with reference to the partitions between the compartments and the feeding-troughs, substantially as shown and described.

SHELBY REED.
